E. GIBSON,

IRRIGATION VALVE,

APPLICATION FILED JAN. 30, 1917.

1,279,857.

Patented Sept. 24, 1918.

Inventor:
Edward Gibson
by his attorney,
Charles R. Searle.

UNITED STATES PATENT OFFICE.

EDWARD GIBSON, OF JERSEY CITY, NEW JERSEY.

IRRIGATION-VALVE.

1,279,857.

Specification of Letters Patent. Patented Sept. 24, 1918.

Application filed January 30, 1917. Serial No. 145,353.

To all whom it may concern:

Be it known that I, EDWARD GIBSON, a citizen of the United States, residing at Jersey City, in the county of Hudson and State 5 of New Jersey, have invented a certain new and useful Improvement in Irrigation-Valves, of which the following is a specification.

In irrigation as now extensively practised, 10 water usually at very low pressure is brought to the field in underground conduits, commonly of vitrified or cement pipes, which are provided with stands or risers at suitable intervals, surmounted by valve casings having 15 a branch or branches through which the field may be flooded or which may be further branched or subdivided for delivering water to the irrigation furrows or channels. It is obvious that in installing a plant of 20 this character the expense of the devices employed must be extremely low to permit operation at a profit, and the valves and other accessories employed must be obtainable at the least possible outlay. The object of this 25 invention is to provide a controlling valve adapted to be connected to the riser, which can be manufactured at a minimum cost, is easily installed and operated by relatively unskilled labor, is adaptable to varying requirements and conditions, readily repaired 30 if broken, and which will serve efficiently and reliably under all the conditions of service to which it is necessarily subjected.

The invention consists in certain novel 35 features and details of construction and arrangement by which the above objects are attained, to be hereinafter described and claimed.

The accompanying drawings form a part 40 of this specification and show the invention as it has been carried out in practice.

Figure 1 is a plan view of a valve and its lateral branches and connections arranged for furrow irrigation.

45 Fig. 2 is a corresponding elevation, partly in vertical section, showing the attachment to the conduit riser.

The succeeding figures are on a larger 50 scale and show the valve alone or with its immediate connections.

Fig. 3 is a side elevation.

Fig. 4 is a corresponding end view.

Fig. 5 is a vertical section taken on the line 5—5 in Fig. 4.

Fig. 6 is a similar view, at a right angle 55 to the preceding figure, taken on the line 6—6 in Fig. 3.

Fig. 7 is a plan view.

Fig. 8 is a vertical section corresponding to a portion of Fig. 6, showing an alternative 60 valve-body.

Similar letters of reference indicate like parts in all the figures.

A is a conduit which may be understood to be connected lengths of concrete pipe of 65 large diameter, laid below the frost line, and A¹ is a riser or vertical outlet extending to or above the surface of the ground, supported and protected by a mass of concrete A² and surmounted by the improved valve. 70

The valve-casing comprises a cover B, a body C, and a base D, each a thin casting formed independently, and separably joined together. The base is a flat annulus having an annular depending flange D¹ on its under 75 face adapted to encircle the upper end of the riser A¹ and secured thereto by cement a introduced in the annular space between the overhanging flange and riser. The base D also has an inner upwardly presented annular lip D² serving as the valve-seat, and is equipped at the outer margin with four or other number of eyes D³ cast integrally with the base for receiving the hooked ends F¹ of rods F by which the parts of the valve- 80 casing are joined.

The body C is a thin cylindrical casting, slightly swelled outwardly to increase its strength, and has in the principal form shown, two oppositely extending nozzles or 90 lateral outlets C¹ C¹ each having spiral flanges or lugs C² C² oppositely located on their ends.

B is the cover comprising a thin circular casting in the form of a plate slightly domed 95 in the center and having a centrally located hollow boss B¹, and four or other number of peripheral bifurcated radial lugs B² B² corresponding to and located above the eyes D³ on the base D.

100 E is the thinly cast valve-disk or plate slightly domed centrally to match to the upward swell of the cover B to lie closely adjacent to the latter when fully elevated so as to afford an unobstructed flow through the 105 valve-casing, and having on the under face of its rim two concentric ribs or ridges E¹ E¹ forming between them a shallow groove

in which is secured an annular gasket E^2 serving to make a tight joint with the valve-seat D^2 when the disk is forced into contact therewith. The disk has a hollow boss E^3 on its under face forming a recess e in which is received a flange G^1 on the extreme lower end of a screw G ; this flange is loosely engaged, with liberty for the screw to rotate, by an annular plate E^4 matching to the mouth of the recess and slipped upon the screw from the opposite end. It is held in the recess by legs or spurs E^5 extending through holes in the bottom of the boss E^3 and riveted or headed on the under face thereof.

The screw G extends vertically from this loose connection with the valve-disk, through the cover and is engaged with the latter to rise or sink therein by the engagement of its threads with corresponding internal threads produced by pouring melted lead into the recess b in the boss B^1 around the same or a similar screw, treated to avoid adherence of the lead thereto, and thus forming a nut B^3 in the cover. At the upper end the screw is squared as at G^2 and after the application of the plate E^4 thereon, is fitted into a correspondingly squared hole in the central boss G^3 of a handwheel G^4 by which the screw may be turned in the lead nut B^3 and the valve-disk E moved vertically relatively to its seat D^2 . The wheel is fixed on the screw by peening the protruding end of the square G^2 .

In assembling the parts a gasket H is interposed between the base and body and a similar gasket H^1 between the body and cover, and the latter applied with the screw and valve-disk attached thereto; the hooks of the rods F are then engaged in the eyes D^3 on the base and the rods inserted in the bifurcations or notches of the lugs B^2 B^2 , and the parts are then drawn strongly together to produce water-tight joints by turning down the nuts F^2 F^2 on the screwthreaded upper ends of the rods into strong contact with the upper faces of the lugs.

J are thimbles adapted to be inserted one into each nozzle C^1 and having each an annular flange J^1 arranged to apply against a gasket H^2 between such flange and the rim of its nozzle. The thimble is drawn into water tight contact by a ring K encircling the thimble on the outer face of the flange J^1 and having oppositely placed hooked arms or dogs K^1 K^1 adapted to engage the spiral lugs C^2 C^2 on the nozzle by a turning movement and thus draw the flange J^1 and its gasket H^2 into strong contact with the rim of the nozzle. Each thimble J , as shown, is slightly tapered and receives one end of a flexible sleeve or hose L , the other end being attached to a branch M from which extend the valve-nozzles having valves, not shown, operated by the valve-

stems M^2 by which the flow through the hose-pipes M^3 to the irrigation furrows may be controlled.

It will be noted that by making the base, body, cover, and valve-disk, each in a thin casting, an extremely light but strong valve of large capacity is produced capable of resisting successfully the moderate water pressures, and other strains to which valves of this character are subjected, and also capable of efficiently controlling the flow.

By making the cover, with its attached valve-disk, and the body and base separable, these parts may be used interchangeably and a broken part replaced from stock. Another advantage of this construction is in permitting bodies of the same diameter but greater height to be substituted when required. Fig. 8 shows one form of an alternative body C^3 having a single large nozzle C^4 on one side, adapted to receive a corresponding large thimble and branch, not shown, through which an unrestricted flow may escape for flooding the field when that system of irrigation is to be practised. The screw G is of sufficient length to permit such substitution, and the rods F may be similarly lengthened or longer ones employed as may be preferred.

The flange D^1 of the base may be threaded or otherwise formed to be screwed or otherwise attached to a correspondingly shaped riser, and other means, as for example an arrangement of spiral lugs or flanges and corresponding engaging dogs similar to the means shown for joining the thimbles to the nozzles, may be employed in separably joining the body to its base and cover.

The screw is preferably cast, for economy in manufacture, and its attachment to the valve-disk is simple and inexpensive as is also the lead nut connection to the cover, but other and more expensive forms and means may be employed in whole or in part if warranted economically.

By outwardly swelling the body and doming the cover and valve disk these parts may be extremely thin castings while retaining the desired strength. All these parts together with the screw are preferably of cast iron. The plate E^4 loosely joining the screw to the valve-disk is preferably of brass to avoid liability of forming a rust joint at this point.

The thimbles J are shown as thin castings and may be of aluminum, but they may be of galvanized sheet iron with the flange J^1 cast directly thereon or otherwise attached or they may be formed of sheet metal by suitable dies.

The body may be a plain cylinder and the cover and valve-disk flat plates having strengthening ribs to reinforce them.

By constructing the ring K with engag-

ing dogs at diametrically opposite points, and by providing ridges on the inner face of the ring intermediate the dogs and opposite each other, the thimble J is drawn into 5 watertight contact with the nozzle C¹ and the pressure distributed equally at all points on the face even though the castings may be slightly irregular.

The cover and base may be used with a 10 body having larger or smaller openings than here shown, or there may be a greater or less number of such openings to be used as may be determined by conditions in the field and adapted to conform to changes in methods 15 of irrigation corresponding to rotation of crops.

I claim:—

1. The irrigation valve described, comprising a body, a base, and a cover, each a 20 thin casting formed independently, a valve-seat integral with said base, a valve-disk within said body and arranged to coact with said seat, a screw connected to said valve-disk with liberty to rotate relatively thereto

and engaged in said cover, said body swelled 25 outwardly and said cover and valve-disk domed, and means for separably joining said body, base, and cover with said body clamped between said base and cover to form a valve-casing. 30

2. In a valve of the character set forth, a base having a valve-seat, a body, a valve-disk within said body and arranged to coact with said seat, a cover having a recess, a valve-operating screw having a flange at 35 its lower end, a plate inclosing said screw above said flange, spurs on said plate extending through said valve-disk and headed thereon, said screw extending through such recess and engaged with said cover by a nut 40 formed in said recess by the introduction of melted metal therein, and means for joining said base and cover and compressing said body between them.

In testimony that I claim the invention 45 above set forth I affix my signature.

EDWARD GIBSON.
